UNITED STATES PATENT OFFICE.

IRVING A. CHURCH, OF ONTARIO, CALIFORNIA.

BENCH-DOG.

1,132,703.

Specification of Letters Patent. Patented Mar. 23, 1915.

Application filed April 2, 1914. Serial No. 829,089.

To all whom it may concern:

Be it known that I, IRVING A. CHURCH, a citizen of the United States of America, residing at Ontario, in the county of San Bernardino and State of California, have invented certain new and useful Improvements in Bench-Dogs, of which the following is a specification.

This invention relates to wood-working and more particularly to a bench dog and saw clamp designed to automatically clamp the material to be worked or operated upon.

The objects of the invention are:—to provide a device of this character which will be simple and cheap in construction; efficient in operation; and which will be adjustable to material of various sizes; also to provide a simple and efficient saw clamp which may be readily swung out of the way, when not in use and which, when in position for use, will contact with operating means connected to said dog.

With these and such other objects in view as may hereinafter more fully appear, my invention consists in the novel arrangement and construction of parts set forth in the specification, more particularly pointed out in the claims, and which are shown in the accompanying drawings, wherein:—

Figure 1, is a plan view of the device. Fig. 2, is a side elevation thereof showing the saw clamp in operative position. Fig. 3, is a front elevation. Fig. 4, is a transverse vertical sectional view taken on the line 4—4 of Fig. 1. Fig. 5, is a detail sectional view of the resilient catch.

Referring to said drawings by numerals:—a suitable bifurcated base of any convenient and preferred material, is provided, along the outer edge of the reduced arms 1, thereof, with flanges 2; the upper surfaces of said flanges being level with the surface of the cross bar 3 of said base. Secured upon said base in any suitable manner, as by the screws 4, is a bifurcated cover 5, the inner corners of the arms of which are supported on blocks or rests 6; which may be integral with the cover, or the base, or may be separate pieces, as preferred.

As will be readily understood from the foregoing, open spaces 7, are formed between the arms 1 and the cover 5. Within the spaces 7 are pivotally mounted; in any convenient and preferred manner, as by the pins 8; levers 9, provided with suitable resiliently actuated catches 10 adapted to

enter the sockets 11, formed in the ends of arms 1, to permit of adjustment of said levers. Pivotally mounted on said levers, as by means of the pins 12, are dogs 13, of the usual and ordinary form, provided with the angularly disposed gripping shoes 14, between which the material is held when the end of such material comes in contact with, and expands the fingers 15 of said dogs.

A curved spring 16, is suitably mounted on the cross bar 3 of the base, the curved ends thereof contacting the fingers 15 of the dogs and retaining the same in place when not in use.

Pivotally mounted on one side of base 3, by means of a rod 17 passing through a suitable bore formed in said base, is a saw clamp provided with arms or end-supports 18, the downwardly projecting portions of which are suitably apertured to receive said rod 17. The side supports 18 have their free ends angularly disposed as at 19, and carry suitably fastened between said angularly disposed ends a rod 20, to form one jaw of a saw gripping device. Arms 21 are pivotally connected to the side supports 18, through the ears 22 which are formed integral with said arms 21, said pivotal connection being accomplished through the reduced ends of a rod 23 entering suitable apertures for their reception. The object of said rod being, to form not only a pivotal connection but also a support and brace for the device. The arms 21 are provided with the angularly disposed ends 24, complementary to the aforesaid ends 19, between which is suitably fastened the rod 25, forming the other jaw of the saw gripping device. Between the lower ends of said arms 21 is fastened a rod 26. Rod 26 is engaged by the grooved end 27, of a bar or link 28, the other end 29 of which is globular in form and adapted to rest in a socket 30 formed in one of the dogs 13.

As will be readily understood, when the saw clamp is in operative position, the insertion of a piece of material between the dogs will cause the link 28 to be forced outwardly against the bar 26, thereby clamping the saw in place between the rods 20 and 24. The dogs operate in the usual manner of such devices, their position being regulated by moving the ends of levers 9 toward or away from each other as the size of material may demand. The resilient catch may be of any well known and usual

design but, as here shown, it consists of a thumb cap 10 provided with a pin 31 encircled by a collar or flange 32. Pin 31 extends through a suitable aperture formed in a cup shaped member 33, and is encircled by a coiled spring 34 interposed between the collar or flange 32 and the cup shaped member. Member 33 is suitably secured to the lever 9 near the operative end 10 thereof.

The device is to be attached, in any suitable manner, to a work bench.

Having described my invention, what I claim as new and desire to secure by Letters Patent, is:—

1. In a device of the character described, a suitable base, arms pivotally secured to said base, dogs pivotally secured to said arms, a saw-clamp hinged to one side of said base, and means interposed between one of said dogs and said clamp whereby said dog may operate said clamp.

2. In a device of the character described, a suitable base, arms pivotally secured to

said base, dogs pivotally secured to said arms, a saw-clamp hinged to said base, means interposed between one of said dogs and said clamp whereby said dog may operate said clamp, and means for adjusting said arms toward and away from each other.

3. In a device of the character described, a suitable base, arms pivotally secured, at one of their ends, to said base, means carried by the other ends of said arms for engaging spaced apertures in said base for securing said arms in desired positions, dogs pivotally secured to said arms, a saw-clamp secured to said base, means interposed between said clamp and one of said dogs whereby said dog may operate said clamp, and means for swinging said saw-clamp below the bench, when not in use.

In testimony whereof I hereunto affix my signature in presence of two witnesses.

IRA A. CHURCH.
